To all whom it may concern:

Be it known that I, Dayton Morgan, of the city of Chillicothe, in the County of Ross, and State of Ohio, have originated, made or produced a several original design, in round relief, of a bust representing Honorable Abraham Lincoln, late President of the United States, and I do hereby declare that the following is a full, clear and exact description, (reference being had to the accompanying photograph making part of this specification,) namely, Head, Shoulders and Breast, cut off below the pectoral muscles, draped with ordinary modern clothing, with a cloak loosely folded over the shoulders and back and across the breast. The head erect and turned slightly to the right.

That I claim as my design and production, and desire to secure by Letters Patent is, the design for a bust as above described herein, set forth and represented in the accompanying print.

Witness,
